UNITED STATES PATENT OFFICE.

CHARLES STOLLBERG, OF TOLEDO, OHIO, ASSIGNOR TO AMERICAN CAN COMPANY, OF NEW YORK, N. Y., A CORPORATION OF NEW JERSEY.

SHEET-METAL LEAD-KEG.

1,200,263.

Specification of Letters Patent.

Patented Oct. 3, 1916.

Application filed July 1, 1913. Serial No. 776,789.

To all whom it may concern:

Be it known that I, CHARLES STOLLBERG, a citizen of the United States, residing in Toledo, in the county of Lucas and State of Ohio, have invented a new and useful Improvement in Sheet-Metal Lead-Kegs, of which the following is a specification.

This invention relates to sheet metal lead kegs and is in the nature of an improvement 10 of the lead keg disclosed in my co-pending application Serial No. 730880 on sheet metal lead kegs, filed November 12, 1912.

An object of the invention is to provide a sheet metal lead keg such as ordinarily contain 15 50 or 100 pounds of white lead, which is provided with a reinforcing or strengthening band on the bottom, the external diameter of which is substantially equal to the external diameter of the usual bead or roll 20 formed on the top of the keg, whereby the kegs may be rolled in straight lines.

Another object of the invention is to provide a sheet metal lead keg having a reinforcing band of the type above indicated, 25 so constructed that the band will not be torn off or stripped from the body member because of hard usage.

As is well known, sheet metal lead kegs are ordinarily constructed to carry 50 or 100 30 pounds of white lead, and in transportation these lead kegs are roughly handled and frequently dropped and thrown around with the result that the kegs will soon be knocked out of shape unless suitable reinforcing 35 means are provided. A reinforcing roll or bead is usually formed integrally with the body member at the top thereof, and in order to strengthen the lower portion of the keg I attach a strengthening or reinforcing 40 band thereto, preferably by spot welding, the band being provided with an inwardly extending rib or shoulder which abuts against the bottom of the keg proper, the band being also provided with an outwardly 45 turned bead of substantially the same outer diameter as the outer diameter of the bead at the top of the keg, to thereby enable the kegs to be rolled in a straight line.

In the drawing forming a part of this 50 specification, Figure 1 is a vertical sectional view of a sheet metal lead keg embodying my improvements, and Fig. 2 is a horizontal section taken substantially on the line 2—2 of Fig. 1.

55 In said drawing the body of the keg is des-

ignated by the reference 10 and, as shown, is provided with the usual integral outwardly turned bead or roll 11 at its top or open end. At the bottom of the body member 10, which, as shown, is drawn seamless, there 60 is provided a shoulder 12 against which abuts the upper edge of a reinforcing or strengthening band 13, the latter encircling the necked-in lower part of the body member 10 and preferably spot welded thereto 65 as shown at 14. The band 13, at its lower edge, is provided with an outwardly turned integral bead or roll 15, the outside diameter of which is substantially equal to the outside diameter of the bead or roll 11. Above 70 the bead 15, the band 13 is provided with an inwardly extended, integral rib, flange or bead 16 which serves as an abutment shoulder against the bottom of the body member 10. The keg is provided with the 75 usual cover 17, having lips 18 adapted to be bent around the bead 11 to secure the cover in place.

From the foregoing description, it will be seen that the abutment flange or rib 16 80 serves to take up or absorb all the shocks on the bead 15, due to the keg being dropped or otherwise roughly handled, thus relieving the spot welds from shearing strains and preventing the band from being displaced 85 and pushed up over the shoulder 12. In actual practice I have found that a reinforcing band constructed as I have herein described it and secured to the body proper of the keg in the manner described, will stand 90 the roughest treatment and the bead may be bent out of shape without impairing the spot welding or displacing the band from its normal position.

Although I have herein shown and described what I now consider the preferred embodiment of my invention, yet it will be understood that various changes and modifications may be made without departing from the spirit of the invention, and all 100 such changes and modifications are contemplated as come within the scope of the claim appended hereto.

I claim:

A sheet metal lead keg of the character 105 described comprising, in combination: a drawn, seamless body member having an integral bottom and provided with a strengthening bead at its top end, said body being necked-in at the bottom thereof; and a 110

strengthening band permanently secured to the body member around the necked-in portion thereof, said strengthening band being provided with a bead of substantially the same diameter as the bead at the top end of the keg, whereby the keg is adapted to be rolled in a straight line, the said band being formed at the bottom end of said necked-in

portion with an integral inwardly extended bead lying against the bottom of the body, 19 and consisting of two members lying in contact one above the other.

CHARLES STOLBERG.
